US0D1017937S

(12) **United States Design Patent** (10) **Patent No.:** **US D1,017,937 S**
(45) **Date of Patent:** **** Mar. 12, 2024**

(54) **HANDLE FOR CLEANING MACHINE**

(71) Applicant: **Tineco Intelligent Technology Co., Ltd.**, Suzhou (CN)
(72) Inventor: **Yongxiong Huang**, Suzhou (CN)
(73) Assignee: **Tineco Intelligent Technology Co., Ltd.**, Jiangsu (CN)

(**) Term: **15 Years**

(21) Appl. No.: **35/515,460**

(22) Filed: **Sep. 29, 2022**

(80) **Hague Agreement Data**

Int. Filing Date: **Sep. 29, 2022**

Int. Reg. No.: **DM/224249**

Int. Reg. Date: **Sep. 29, 2022**

Int. Reg. Pub. Date: **Oct. 28, 2022**

(30) **Foreign Application Priority Data**

(57) **CLAIM**

The ornamental design for the handle for cleaning machine, as shown and described.

DESCRIPTION

1. Handle for cleaning machine
  - 1.1: Front
  - 1.2: Back
  - 1.3: Left
  - 1.4: Right
  - 1.5: Top
  - 1.6: Bottom
  - 1.7: Perspective
  - 1.8: Perspective
  - 1.9: Enlarged view of part A marked in 1.3
  - 1.10: Enlarged view of part B marked in 1.5
  - 1.11: Enlarged view of part C marked in 1.6
- The broken lines depict portions of the handle for cleaning machine that form no part of the claimed design.

1 Claim, 11 Drawing Sheets
